UNITED STATES PATENT OFFICE.

CLAUDE TESTE, JR., OF LYON, FRANCE.

FIRE-EXTINGUISHING DEVICE.

1,379,139.

Specification of Letters Patent.

Patented May 24, 1921.

Application filed January 7, 1918. Serial No. 210,678.

To all whom it may concern:

Be it known that I, CLAUDE TESTE, Junior, a citizen of the French Republic, residing at Lyon, in France, have invented certain new and useful Improvements in Fire-Extinguishing Devices, of which the following is a specification.

This invention relates to improvements in fire extinguishing devices.

10 Fire extinguishers generally consist of a receptacle containing liquid of appropriate composition which is projected by means of a pump placed inside or outside the receptacle and which is worked by hand, or by 15 means of gases produced at the moment by various combinations.

These devices all offer some drawbacks; those with pumps are complicated, costly and necessitate a fatiguing and troublesome 20 working for the expulsion of the liquid. The others are uncertain in working and being made of glass are liable to be inadvertently broken during transport or various manipulations, or owing to accidents, 25 shocks, etc.

The subject of the invention is an extinguisher of great simplicity having an assured working whatever manipulations or shocks it may be subjected to.

30 Its receptacle incloses the extinguishing liquid and the gas under pressure required for its total expulsion at the moment of use, which is effected by the simple opening of a valve arranged for that purpose.

35 The annexed drawing illustrates as an example of realization of the invention a small portable apparatus: Figure 1 is a section of the head of the extinguisher, the valve being shown closed. Fig. 2 is a section showing 40 the valve open. Fig. 3 is a section and Fig. 4 an elevation showing a modified form of valve.

The device comprises a cast cylindrical head g , Figs. 1 and 2, the base of which is 45 so shaped as to fit perfectly and conveniently on the neck r of the receptacle to which it is autogenously soldered. This head has a lateral pipe s , the threaded end of which is closed with a screw-stopper s^1 50 after introduction of the compressed air and also serves to receive the pipe for the introduction of the compressed air.

The said head g is provided throughout its length with a bore having two diameters, 55 connected by a conic part forming the seat f^1 of a plug valve t , which is screwed into the

hole of large diameter threaded for this purpose. This plug-valve t is also provided with a bore having two diameters connected by a conic seat u of a needle-valve screwed 60 into the hole of large diameter and having a hand wheel w for its operation. The valve t ends in a six sided head t^1 , and it has at a given place of its length a circular recess x communicating with the bore by means of 65 transverse conduits y .

For filling of the receptacle with the extinguishing liquid the valve t is unscrewed with a nut wrench and completely removed together with the needle-valve v , and the 70 liquid is poured in. The filling being effected, the valve t is screwed in again care being taken to force it on its seat f^1 , then the needle valve v is put into the position of Fig. 2. If at this moment the tube conducting compressed air is screwed on the pipe s and the air admitted, it will enter above the liquid by passing through the neck x and the conduits y . When the charge of compressed air has attained the desired pressure 80 the air admission cock is closed, then the needle valve v is strongly screwed on its seat u , all communication of the charge of compressed air with the outside thus being interrupted. 85

To use the extinguisher it is sufficient to operate the wheel w in order to sufficiently unscrew the needle valve v and uncover the conduits y . The extinguishing liquid will then escape under the effect of the air pressure 90 through the pipe s , from which care will have been taken to previously remove the stopper s^1 .

When the needle-valve v is of one piece the closing of the same on its seat takes place 95 by screwing it firmly on the seat; thereby insuring an absolutely perfect closing, but on the other hand the opening of the needle-valve requires considerable effort, which is an inconvenience. The latter is obviated by 100 the construction of the needle-valve in two parts, as shown by Figs. 3 and 4. The rod v is provided with an axial blind hole c^1 and with a transverse hole d^1 cutting through the periphery of the hole c^1 as 105 shown in Fig. 6. The conic point z comprises a cylindrical tail-piece a^1 having the diameter and length of the hole c^1 which serves as a casing therefor, and this tail-piece has an annular recess b^1 co-inciding 110 with the transverse hole d^1 when the said tail-piece a^1 is in place. In this position a

pin e^1 is inserted into the hole d^1 for the purpose of keeping the piece z in place.

It can be understood that this construction allows the piece z and the rod v to turn 5 on their axes but without being able to separate from each other, hence when the needle-valve is screwed down the piece z stops turning when it is applied on its seat, but the rod v continues its rotation while 10 effecting a progressive pressure on the piece z to apply it firmly on its seat u .

The opening of the needle-valve is thus facilitated and only requires a slight effort.

The construction could be reversed without inconvenience, that is to say, the male 15 part would be the rod v and the point would be arranged to contain it.

What I claim as my invention and desire to secure by Letters Patent of the United 20 States is:—

1. A fire extinguisher comprising a re-

ceptacle having a head provided with a bore of two diameters, a screw plug valve in said head having an axial bore of two diameters, a screw needle valve arranged in the larger 25 bore in the plug valve, and a lateral duct in the head through which the compressed air is admitted and the extinguishing liquid is expelled when the apparatus is in use, the screw plug valve being provided with lateral conduits communicating with said duct.

2. A fire extinguisher as in claim 1 wherein the screw needle valve comprises a point 30 adapted to rotate independently of the main rod of the valve.

In witness whereof I have signed this specification in the presence of two witnesses.

CLAUDE TESTE, JUNIOR.
